US00D808772S

(12) **United States Design Patent** (10) Patent No.: **US D808,772 S**
Rothbaum et al. (45) Date of Patent: **** Jan. 30, 2018**

(54) **STRAP WITH CORD ATTACHMENT
MECHANISM FOR A CORD MANAGEMENT
SYSTEM**

- (71) Applicant: **CJD LLC**, New York, NY (US)
- (72) Inventors: **Wayne Philip Rothbaum**, New York, NY (US); **Allison S. Conner**, Brooklyn, NY (US); **Robert B. Curtis**, San Francisco, CA (US); **Jonas K. Damon**, New York, NY (US); **Daniel A. Sanchez**, Brooklyn, NY (US)
- (73) Assignee: **CJD LLC**, New York, NY (US)
- (**) Term: **15 Years**
- (21) Appl. No.: **29/597,142**
- (22) Filed: **Mar. 14, 2017**
